H. F. GREENAWALT,

TIME CONTROLLED HEAT REGULATOR FOR FURNACES.
APPLICATION FILED FEB. 15, 1918.

1,331,639.

Patented Feb. 24, 1920.

UNITED STATES PATENT OFFICE.

HARRY F. GREENAWALT, OF PHILADELPHIA, PENNSYLVANIA.

TIME-CONTROLLED HEAT-REGULATOR FOR FURNACES.

1,331,639.

Specification of Letters Patent.

Patented Feb. 24, 1920.

Application filed February 15, 1918. Serial No. 217,391.

To all whom it may concern:

Be it known that I, HARRY F. GREENAWALT, a citizen of the United States, and a resident of Philadelphia, county of Philadelphia, and State of Pennsylvania, have invented a certain new and useful Time-Controlled Heat-Regulator for Furnaces, of which the following is a specification.

The principal object of the present invention is to provide a simply constructed and efficiently operating mechanism designed to automatically close and open, at a predetermined time, the fire-door and the draft-door, respectively, of a furnace. Other and further objects of the present invention reside in the provision of certain new and novel arrangements, combination and connection of parts for rendering the invention practical according to commercial standards.

The invention consists of the improvements hereinafter described and finally claimed.

The nature, characteristic features and scope of the invention will be more fully understood from the following description taken in connection with the accompanying drawings forming part hereof and in which:

Figure 1 is a view in front elevation of a furnace equipped with a regulator, showing one embodiment of the principles of the present invention.

Fig. 2 is a view in side elevation thereof.

Fig. 3 is a view in section of a time-piece and its complemental casing.

Fig. 4 is a view in section taken upon the line 4-4 of Fig. 3.

Fig. 5 is a fragmentary view in front elevation of the spring actuated fire-door.

Fig. 6 is a similar view of the spring actuated draft-door.

Fig. 7 is a perspective view of the fire-door detent.

Fig. 8 is a similar view of the draft-door release.

Fig. 9 is a fragmentary view in side elevation of the draft-door illustrating the relation of parts prior to the release being operated, and

Fig. 10 is a fragmentary view in cross-section illustrating a position of the alarm-arbor extension hereinafter referred to.

For the purpose of illustrating my invention, I have shown in the accompanying

drawings one form thereof which is at present preferred by me, since the same has been found in practice to give satisfactory and reliable results, although it is to be understood that the various instrumentalities of which my invention consists can be variously arranged and organized and that my invention is not limited to the precise arrangement and organization of the instrumentalities as herein shown and described.

In the drawings 10 designates a furnace 65 having the usual fire-door 11 and draft-door 12, which doors are provided with hinge-lugs 13 having pivotal relation, by means of pintles, with hinge-lugs 15 upon the front plate of the furnace. According 70 to the present invention, one pintle of each of said doors is removed and a pintle 16 substituted therefor. The drawings show this substitution as having been made with respect to the uppermost pintles. Such pintles 75 project well through the hinge-lugs and are screw-threaded for nut reception. Around each pintle is coiled a spring 17 one end of each spring being caused to impinge against a door and the opposite end against 80 the front plate of the furnace. As clearly shown in Fig. 5, the ends of the spring freely bear against the fire-door and furnace-plate so that the tendency of the spring is to maintain said door in closed position. 85 In Fig. 6, the ends of the spring are fixed, as by screws 18 or equivalent devices, to the draft-door and furnace-plate, so that the tendency of said spring is to maintain said door in open position. By means of the 90 nuts 19 the springs 17 may be tightened to develop friction both between the coils of the spring and between the members 15 and 13 whereby the doors 11 and 12 are caused to move less quickly. Obviously by 95 loosening the nuts 19 an opposite effect is procured. No other alteration of a standard furnace is required in the application thereto of the regulator of the present invention. In order to maintain the fire-door 100 in open position against the action of its complemental spring, a detent is employed, see Fig. 7, one end of which has pivotal relation as at 21 with the front plate of the furnace and the opposite end of which is 105 shaped to arrest said door. As clearly shown in Fig. 7, such detent comprises an elongated strap 22 having its ends extended

at right angles in opposite directions of which the end 23 is apertured to accommodate a pivot member and of which the other end 24 terminates in a depending lip 25 for engagement with the inner face of the fire-door. The draft-door it will be understood is maintained closed by the usual lip 26 thereof engaging a catch 27 on the furnace plate, see Fig. 9. In order to permit the draft-door to assume an open position through the coöperation of its complementary spring, a release in the form of cam, see Fig. 8, is employed, pivoted as at 28 to the furnace-plate. As clearly shown in Fig. 8, such release comprises an angular-shaped member provided with a cam portion 29 which is positioned in abutting relation with the underside of the lip 26' of the furnace door. To the rear of the cam surface, said release is provided with a projection 30. When the release is operated around its pivot point in a manner to presently appear, the cam surface raises the lip 26' free of the catch 27' whereupon the spring of the door causes the same to assume an open position. The projection 30 serves the function of initially starting the outward movement of the door simultaneously with the raising of the lip from its seat upon the catch 27'.

A description will now be given of the detent and cam operating mechanism. Suspended above the furnace, as by the rafters 31, is a housing or casing 32 containing a time-piece 33 of the type styled alarm-clocks, the front of the casing having an opening therethrough in which the time-piece is mounted with its face exposed through said opening. In order to securely sustain the time-piece in position, use is made of a clamping device shown in the drawings as comprising a band 34 fitted over the time-piece of which one end is apertured for engagement with the hook 35 of a bolt 36 penetrating the casing bottom and secured in position by means of a nut 37 and a lock-nut 38, and the other end of which has fixed engagement with the slotted end 39 of a bolt 40 which passes through an opening in the casing bottom and may be adjusted vertically therethrough by means of the nut 41. The alarm winding-key complementary to the arbor of the time-piece, is removed and an extension arbor 42 substituted therefor. Such extension has a screw-threaded socket 43 at its inner end, a screw-threaded piece 44 at its outer end. The socket 43 is fitted to the arbor aforesaid and the winding-key 45 previously removed, is fitted to the pin 44, see Fig. 3, which pin projects through the rear wall of the casing 32. The arbors for alarm setting, time winding and time setting are similarly provided with extension arbors as clearly illustrated in Fig. 3. A partition 46 may be

present within the casing to serve as a bearing for the arbor extensions. The alarm-arbor extension 42 is provided with a laterally extended opening 47 therethrough, see Figs. 3, 4 and 10 to accommodate a cord, 70 belt, rope, chain or similar medium which passes therethrough. In the drawings, a chain 48 is illustrated. Such chain, which is continuous, passes horizontally through the casing sides over pulleys 49 journaled 75 to the casing outer sides and then passes vertically before the furnace-plate, one end of said chain being secured to the fire-door detent and the other end being connected to the damper-door cam, see Figs. 1 and 2. 80 The time-piece casing may be provided with a door 50 for gaining access to the interior thereof.

A description will now be given of the mode of operation of the above described 85 regulator. The alarm is set for the desired hour of escapement, the furnace fire banked, the fire-door being caused to remain in open position by reason of the pivotal detent, the damper door of course being in closed position. With the escapement of the alarm arbor, the arbor extension partially rotates so as to cause the vertical runs of the chain to be drawn upwardly, see Fig. 10, thus raising the detent free of the fire-door to 95 permit it to close by reason of its complementary spring and at the same time causing the damper-door cam to raise the lip thereof from its catch to permit the damper-door spring to move it to open position. 100

It will now be apparent that I have devised a novel and useful construction which embodies the features of advantage enumerated as desirable in the statement of the invention and the above description and while 105 I have in the present instance shown and described the preferred embodiment thereof which has been found in practice to give satisfactory and reliable results, it is to be understood that the same is susceptible of 110 modification in various particulars without departing from the spirit or scope of the invention or sacrificing any of its advantages.

What I claim is:

Apparatus of the character stated comprising in combination a furnace equipped with complementary fire and draft doors, a spring for closing the fire door when released and a spring for opening the draft door when 120 released, a detent pivoted to said furnace the free end of which is adapted to engage the upper rim of the fire door for retaining same in open position, a lip and catch connection between said furnace and draft door 125 for maintaining said door closed, a cam pivoted to the furnace and adapted when operated to move said lip over said catch to release the draft door, a time-set prime mover having an apertured extension arbor 130

and a continuous flexible connection passing through said aperture one end of which connection is secured to said detent and of which the other end of said connection is secured to said cam whereby upon operation of said arbor the intermediate portion of said connection is wound around said arbor to cause the respective ends of said connection to move said detent and cam around their respective pivots for releasing said doors.

In testimony whereof, I have hereunto signed my name.

HARRY F. GREENAWALT.
